UNITED STATES PATENT OFFICE.

FRED E. RINER AND FRED L. THOMAS, OF RIVERDALE, KANSAS.

FEEDER AND BAND-CUTTER.

SPECIFICATION forming part of Letters Patent No. 759,552, dated May 10, 1904.

Application filed August 29, 1903. Serial No. 171,197. (No model.)

To all whom it may concern:

Be it known that we, FRED E. RINER and FRED L. THOMAS, citizens of the United States of America, residing at Riverdale, in the county of Sumner and State of Kansas, have invented new and useful Improvements in Feeders and Band-Cutters, of which the following is a specification.

The invention has special reference to automatic self-regulating feeders and band-cutters for threshing-machines.

The general objects are to improve the same so that the number of parts is reduced to the minimum and so that the mechanism employed is simple and economic in construction and operation and so that a uniform feed is effected to the separator-cylinder.

The separate component parts of the invention are not new of themselves, except the securing-clamps and shifting mechanism; but the invention consists in the novel combination, arrangement, and disposition of the parts, as set forth in this specification and specifically claimed in the appended claims and as also shown in the accompanying drawings, forming part of this specification.

We have not set out the details of construction, as such details are well known to those skilled in the art and would confuse the reader in a full understanding of the essential features of the invention.

Figure 1 is a side elevation, the near side of the frame being removed, so as to show the relative positions of the conveyer, the cylindrical band-cutter, the beater, and the cylinder. Fig. 2 is a side elevation of the frame, showing the arrangement of the operating-pulleys. Fig. 3 is a view of the shifting device through the line 3' 3', Fig. 4, which is a view of the shifting device looking from the right-hand end of the conveyer as shown in Fig. 2. Fig. 5 is a section of the beater-blades and clamp for holding the same in place on the cylinder-frame, with a dotted outline of the band-cutter blade, which is secured to its cylinder-frame by the same device; and Fig. 7 is a top view of the same. Fig. 6 is a section of the adjustable rest for the shifting-lever.

Like reference-numerals indicate like or

corresponding parts throughout the several 5° views.

1 is the framework, of which only sufficient is shown to show the manner of mounting the several parts of the feeder and band-cutter, also the cylinder. 55

2 is the separator-cylinder, and 3 is its shaft, suitably mounted in the framework.

4 is the conveyer, arranged to carry the straw from the exit end of the carrier, which may be mounted at 64 to the separator-cylinder. 60 The conveyer may consist of the sides 5 5, bottom 6, preferably of canvas and conforming to the carrier 7, which runs on the pulleys or sprockets 8 and 9, which are mounted on shafts 10 and 11, respectively, and is operated 65 by the pulley 12, sprocket-chain 13, and wheels 14 15.

16 16 are stay or tie rods extending from one side to the other of the conveyer-frame to strengthen the same, and they may also 70 serve as a rest for the loaded side of the carrier 13. The outer end of the conveyer, it is seen, is secured to the framework through the shaft 10, which is mounted in boxing thereon. The conveyer is also upheld by the 75 jointed rod 17, (there are two, one on each side of the conveyer,) pivoted to the frame at 18 and supporting the rod 19, which extends from one side of the conveyer to the other through the slots 20 20 in the respective side pieces. 80

To a hook 21 on the jointed rod 17 is attached one end of the spring 22, whose other end is swiveled, 23, to the rod 24, which is adapted to be screwed through the beam 25 and which is also provided with a crank-handle 26, 85 whereby the tension of the spring may be readily adjusted. The inner bottom end of the conveyer terminates in a lip 27, which overhangs the corresponding lip 28, extending upwardly from the concave, so as to guide 90 the straw properly between the cylinder and concave and so as to permit the up-and-down motion of the inner end of the conveyer, which will be hereinafter explained. The lip 28 may be hinged, 29, and held in its normal 95 position, as shown in Figs. 1 and 2, by any suitable means, illustrated as by a peg 30 in the frame 1, so that by letting down the lip

28 the conveyer may be lowered entirely clear of the cylinder, as will hereinafter be explained. The upward movement of the inner end of the conveyer may be limited by the bars 5 27' 27', extending outwardly from the sides 5 5 and engaging the frame 1, or by any other suitable means.

31 is a cylindrical beater-frame on the shaft 32, having mounted on its periphery the 10 beater blades or knives 38. There may be any suitable number or arrangement of these knives or blades; but we prefer in the ordinary threshing-machine to arrange them in four rows parallel with the shaft, two of the 15 rows having seven and the other two rows having eight blades, arranged alternately, making thirty blades in all. The device for securing these blades to the frame is novel and new with us and is shown in detail in 20 Figs. 5 and 7. The clamp 35 has a screw-shank which is adapted to be screwed into the frame of the cylinder, and its head is provided with a slot 36, as shown, and at the outer end of the slot and secured in the walls thereof 25 is a bolt 37. The blade 38 is notched, 39, to engage the bolt 37 and has its diagonal cutting and beating edges 40 serrated and sharpened, whereby any bands which may have escaped the band-cutter are certain to be severed. By having the notches 39 39 on both 30 ends of the blade 38 and the two diagonal cutting and beating edges, as shown, the same is reversible, so that when one side has become worn the blade may be reversed to present 35 the other side to the wear. The inner edge of the blade is slightly beveled to conform to the bevel of the inner end of the slot. When the clamp is removed from the frame, the blade is inserted in the clamp from the under side by 40 bringing the slot or notch 39 in engagement with the bolt 37 and swinging the blade on the bolt up through the slot 36 into the position shown in the drawings, and the shank may then be screwed down in the frame of the cylinder until the under side of the blade rests 45 against the surface of the frame. In Figs. 5 and 7 the right-handed side represents the side which comes in contact with the straw. The screw end of the clamp leads. The slotted end 50 trails. In this manner the blades are held most securely in place on the frame and may also be readily removed and replaced. The cutter-knives of the band-cutter, it may be appropriate to explain now, are provided with devices 55 for securing them to their frame similar to those just described, the only difference being in the shape of the blade 43, which instead of two cutting edges has but one and which is not reversible and which consequently extends 60 outwardly farther from the frame, all of which is indicated by the dotted outline in Fig. 5.

The band-cutter consists of the cylindrical frame 41 on the shaft 42, suitably mounted in the frame of the machine, the cutters hereto-

fore described being mounted on the cylindrical frame. Preferably we arrange the cutter-knives in three rows for the ordinary machine parallel with the shaft—eight in a row, twenty-four in all.

It is understood, of course, that the number 70 of blades of the beater and cutter, as well as their arrangement, may be varied to suit the needs of the machine without departing from the spirit of the invention.

The band-cutter is mounted just above the 75 end of the conveyer and is adapted to come in contact with the bands as the straw is carried along on the conveyer and also aids in pushing the uppermost portions of the straw ahead. The beater is arranged inwardly and upwardly 80 from the end of the conveyer and is adapted to come in contact with the straw as it comes from the conveyer, more particularly to come in contact with the upper portions thereof, so as to effect the more rapid feed from the top 85 of the bunch. The cutter should have a speed of about three hundred revolutions per minute, while the speed of the beater may be six or eight hundred. With this arrangement of the increasing speed of the feeding devices 90 toward the cylinder it is clear that the tendency to choking is avoided somewhat.

The cylinder-shaft 3 carries the pulley 44, and the beater and band-cutter shafts 32 and 42 carry the pulleys 45 and 46, respectively. 95 The pulleys are operatively connected by the belt 47, which is provided with a tightener 48, pivoted at 49, to insure the proper tension of the belt. The sizes of the pulleys represent in a general way the relative speeds of the 100 several shafts.

The pulley 12 is loosely mounted on the shaft 10 whereby the conveyer is driven and is provided with one or more inwardly-projecting pins 51 51. Adjacent to the ends of these pins 105 is another pulley, 50, keyed to the shaft 10 and having mounted thereon by the pivot 53 a lever 52, whose inner end is hooked, 54, so as to engage one of said pins 51 51, and whose outer end is extended around the rim of the 110 pulley, as shown in Fig. 4. The lever is normally held in engagement with the pin 51 by the spring 55 connecting one arm of the lever to a lug in the side of the pulley 50, as indicated in Fig. 3, or by any other suitable means. 115 A long lever 57, pivoted to the frame 1 at 58, has its outer and heavier end resting on the outwardly-extending arm 61 of the plate 60, which is slotted, 63, and therethrough by the screw 62, adjustably attached to the side 5 of the conveyer-frame. The other end of the lever 57 is bent toward the turned-over end 56 of the lever 52, as indicated at 59 in Fig. 4. It is sufficient to state that these parts are so arranged that normally, as indicated in the 120 drawings, the ends 56 and 59 are not in contact with each other, so that, the spring 55 holding the hook 54 in contact with the pin 51, the 125

shaft 10 is caused to revolve with the driving-pulley 12; but as the inner end of the conveyer 4 is depressed, which depression may be caused by too large a bunch of straw coming between the conveyer and the band-cutter, thus permitting the longer and heavier end of the lever 57 to lower and the other end to become more elevated, such end 59 engages the end 56 of the lever 52, thereby throwing the hook 54 out of engagement with the pin 51, thereby permitting the driving-pulley 12 to revolve without carrying the pulley 50 or shaft 10 with it, and thereby arresting the operation of the conveyer until the inner end of the conveyer has elevated high enough to bring the ends 56 and 59 out of contact with each other, when by a reverse of the operation just described the conveyer will again be caused to operate.

Another feature of the invention is the arrangement of the conveyer and its connections so that the inner end may be pulled down by lowering the lip 28, as heretofore described, and pulling the inner end downwardly against the tension of the spring 22, letting the conveyer as a whole swing on the shaft 10. The rod 19 will slide upward toward the other end of the slot 20 toward the shaft 10, so that the spring 22 need not be removed; nor is it necessary to remove any of the other connections. The operator or machinist, may thus readily have access to the separator-cylinder for any desired purpose by simply pulling down the inner end of the conveyer and without removing any of the operating connections.

What we claim as new, and desire to secure by Letters Patent, is—

1. In threshing-machines, the combination of the frame; the conveyer; the driving-shaft therefor mounted on the frame; the exit end of the conveyer being supported by a spring connection, and the other end being supported by the driving-shaft; the cylinder arranged above the exit end of the conveyer and provided with blades projecting from the surface thereof; automatic shifting devices for stopping and starting the conveyer operated by the movement of the exit end of the conveyer

against and with the tension of the spring connection; and suitable driving mechanism and operative connections therefor.

2. In threshing-machines, the combination of the frame; the conveyer; the cylinder arranged above the exit end of the conveyer and having blades projecting from its surface; the exit end of the conveyer being supported by a spring connection, the driving-shaft for the conveyer, a member keyed thereon and carrying a lever provided with a hook adapted normally to engage the pin on the driving-pulley; the driving-pulley loosely mounted on the driving-shaft having pins projecting therefrom and adapted to engage said hook; another lever pivoted on the frame and connecting the conveyer and the first-mentioned lever for bringing said hook into and out of engagement with the pins; and suitable operative connections and driving mechanism therefor.

3. In feeding mechanism for threshing-machines, the combination with the cylindrical frame; the slotted clamp having a screw-shank adapted to be screwed into the frame, the slotted portion extending along the surface of the frame; the blade extending through the slot and adapted to be secured therein by compression between the slotted portion and the frame.

4. In feeding mechanism for threshing-machines, the combination of the cylindrical rotary frame; the slotted clamp having a screw-shank adapted to be screwed into the frame, the slotted portion extending along the surface of the frame and having a bolt across its outer end, its inner end being beveled; the blade adapted to extend through the slot, and having a notch and bevel to engage respectively the bolt and beveled end of the slot.

In testimony whereof we have hereunto set our hands in the presence of witnesses.

FRED E. RINER.
